(57) CLAIM

The ornamental design for a large pad holder, as shown and described.

DESCRIPTION

FIG. 1 is a perspective view showing the front, left side and bottom of the large pad holder showing my new design.

FIG. 2 is a perspective view showing the front and bottom thereof.

FIG. 3 is a perspective view showing the front and top thereof.

FIG. 4 is a left side view thereof.

FIG. 5 is a right side view thereof.

FIG. 6 is a front view thereof; and,

FIG. 7 is a rear view thereof.

The paper pad depicted by means of broken lines in FIG. 1 has been shown for illustrative purposes only and forms no part of the claimed design.
